Primary Examiner — Steven J Czyz(57) **CLAIM**

The ornamental design for a sleeve for packaging bottle, as shown and described.

DESCRIPTION

FIG. 1 is a front elevational view of a sleeve for packaging bottle showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a rear, top and left side perspective view thereof;

FIG. 8 is a front, bottom and right side perspective view thereof; and,

FIG. 9 is a front, top and right side perspective view showing the sleeve for packaging bottle in a use state.

The broken lines in the drawings illustrate environmental subject matters that form no part of the claimed design.

1 Claim, 9 Drawing Sheets(56)
